UNITED STATES PATENT OFFICE.

ROBERT F. COOKE, OF BROOKLYN, NEW YORK.

DESIGN FOR A MATCH-SPLINT.

SPECIFICATION forming part of Design No. 25,175, dated February 18, 1896.

Application filed December 27, 1895. Serial No. 573,541. Term of patent 14 years.

To all whom it may concern:

Be it known that I, ROBERT F. COOKE, of Brooklyn, Kings county, New York, have invented and produced a new and original Design for Match-Splints, of which the following is a specification, reference being had to the accompanying drawing, which represents a perspective view of my newly - designed match-splint.

The leading feature of my design consists of a flat match-splint having a series of parallel transverse ridges and intervening perforations.

a is a flat match-splint provided at one of its faces with a series of parallel transverse ridges *b*, extending from edge to edge of the splint. Between the ridges *b* are arranged a series of perforations *c*.

What I claim is—

The design for a match-splint, substantially as herein shown and described.

ROBERT F. COOKE.
